UNITED STATES PATENT OFFICE

ORVILLE C. JOHNSON, OF AURORA, ILLINOIS

DOOR CLOSURE

Application filed August 12, 1931. Serial No. 556,653.

This invention relates to closure operators and more particularly to that type involving a door made in sections which are hinged together and which is elevated in the opening operation. It has its special application to a garage door with which a counterbalance is used which counterbalance may be employed as an operating means for the door.

The object of the invention is to simplify the construction of such door so that it will demand but a minimum of space in its opening and closing so that the counterbalance will not have to travel to the floor of the garage in the performance of this function.

Other objects and advantages of the invention will hereinafter appear in the following description and the novel features thereof will be particularly pointed out in the appended claims.

Like reference numerals indicate like parts throughout the several figures of the drawings, in which

Fig. 1 is an elevation of the door as it is seen from the inside of the garage and in closed position,

Fig. 2 is a sectional view on the line 2—2 of Fig. 1,

Fig. 3 is a vertical section of the door showing in dotted lines its nearly open position, and

Fig. 4 is a detail of the slide bar.

The door is comprised of sections 10 and 11, the lower door 10 being slightly greater in height than the upper section 11. These two parts of the door are joined together by hinges 12 and the door as a whole is hinged at 13 to the overhead beam 14 in such a way that the upper section when the door is open will occupy a position in front of the garage, as shown in Fig. 3 in dotted lines.

Along the jambs 15 and 16 of the building are mounted angle guides 17 and 18 and it will be appreciated that the outstanding web of this angle guide indicated by the numeral 19 occupies a position behind the door. As shown in Fig. 2, this web when the door is in closed position makes a substantially tight joint with the abutting door sections.

On the lower section of the door there is mounted a pair of slide bars 20 and 21 which

have a length substantially one-half the height of the lower door section. The upper end of the slide bar is attached to the lower door section at substantially its medial line. On the same door section is mounted hand grips 22 and 23, the hand grip 22 being employed to lift the section, while the hand grip 23 is designed primarily for buckling the door.

A counterbalance 24 is provided for the door and is connected to the slide bars on the lower section of the doors through the medium of a pair of cables 25 and 26 passing over suitable pulleys which will now be described in detail.

Pulley supports 27 and 28 similar in all respects in their detail construction are suitably secured to the overhead beam 14 on each of which is mounted a pair of pulleys, on respectively horizontal and vertical pivots, designed in the well-known manner to change the direction of travel of the cables. The cables themselves carry traveling pulleys 29 and 30 at their lower ends, which traveling pulleys are designed to move along the length of the slide bars in the upward movement of the door. The position of these pulleys, when the door is closed, is shown in full lines in Fig. 3, and their position, when the door is open, is shown in dotted lines in Fig. 3.

Both cables pass over the pulley 31 and are attached to the counterbalance 24. It will be appreciated that the counterbalance may be located at the opposite side of the door when pulley supports similar to 27 and 28 will be provided but which will enable the cable to be run in a direction opposite to that shown in the drawing. If the pulley supports shown may be said to be right hand pulley units, then left hand pulley units of identical construction will produce this change of direction. It will also be appreciated that the counterbalance may be located at the rear of the garage and centrally thereof, in which case one right hand pulley support and one left hand pulley support may be employed as elements of the cable runway.

From the detail description of the several parts the operation of the device will be ap-

parent. A résumé only, therefore, is necessary to a full disclosure of the invention.

Reference is had to Fig. 3 of the drawings and to the full line disclosure found there.

- 5 The lifting cable is shown as exerting a pull upon the lower section of the door at the point indicated by the numeral 32, and when the door sections are buckled by a push on the hand grip 23, the counterbalance pull at the 10 point 32 will be sufficient to enable one to lift the doors through a gripping of the hand grip 22. In this lifting operation the flange or web 19 of the angles 17 and 18 will prevent the lower section of the door from entering the garage, but the lower end of the door section 10 will ride upon this flange or web in the ascent of the door to the dotted line position shown in Fig. 3.

- 15 During the door's ascent the traveling pulley will move from its position at the upper end of the slide bar as shown in full lines in Fig. 3, to a position at the lower end of the slide bar shown in dotted lines in Fig. 3. Two results are accomplished by the provision of the slide bar and traveling pulleys. The first is to permit the counterbalance 20 to have sufficient travel from its elevated position, shown in Fig. 1, to the floor of the garage to accomplish the movement of the sectional door to its open position; it will be appreciated that if the cable were attached to the 25 lower section of the door at a lower position than that indicated by the numeral 32, the counterbalance would reach the floor before the complete opening of the door had been accomplished. Secondly, the transferring of the pull upon the lower section of the door from the point 32 to the point 33 (see Fig. 3) reduces the inward pull upon the door tending 30 to bind the lower end of the section 10 upon the flange 19 and therefore permits the more easy operation of the door in both ascent and descent.

35 It will be appreciated that the parts form-

ing the door and operator herein described are all standard parts and that they may be shipped as a unit to be inserted in the opening of a garage of a given size. In other words, the device herein described may be 70 deemed a standardized door for garages. The door may be provided with a latch if desired so that it may be securely locked and this may be operated automatically by a pull upon the counterweight, such as is illustrated in my prior patents.

75 The slide bars 20 and 21 permit the easy operation of the door. There is less leverage necessary when the cables are working from the upper part of the slides as the door in starting requires less counter-balancing. In the ascent of the door, when the pulleys roll to the lower portion of the slides, additional leverage is secured and permits the door to go to the top with very little exertion on the part of the operative. It will 80 also be noted that the operator is one which does not require a spring, making the operation more positive and avoiding the necessity of adjustments inherent in a spring operated door.

85 Having described my invention what I claim is:

90 In a manually operated door, a door proper composed of upper and lower sections hingedly connected, said sections being of substantially the same height and adapted to lie outside the frame in their flexed and open position, and means for counterbalancing the weight of said door comprising a 95 cable and weight, said cable being connected to the lower section of said door by a sliding connection, whereby the initial pull upon the door will be at substantially the central portion of said lower section and the final 100 pull upon the door will be at substantially the lower portion of said lower section.

105 In testimony whereof, I affix my signature.

110 ORVILLE C. JOHNSON.
